NECKTIE RACK

Alfred J. Hort, Great Neck, N. Y.

Application March 12, 1949, Serial No. 81,173

2 Claims. (Cl. 211—87)

1

This invention relates to necktie racks and particularly to the type of necktie rack disclosed in Patent No. 1,940,951 of December 26, 1933.

The necktie rack shown in the above mentioned patent comprised two bars pivotally connected by a plurality of wire hooks. The lower bar was arranged to be secured to a support so that it was stationary while the other bar was designed to be manually actuated whereby the hooks assumed either a tie engaging or releasing position. Manual actuation of the movable bar forced all of the hooks simultaneously into either of the two positions mentioned.

According to the present invention, a tie rack is disclosed which is of double the capacity of the one above described and which is nevertheless simply and easily actuated into tie engaging or releasing position. This is effected by doubling the number of wire hooks, spacing them closer together, and extending every other hook for a considerable distance below adjacent hooks so that neckties may be maintained on two levels and locked or released through a single operation, means being further provided to facilitate the manual operation of the movable bar.

The invention will be further understood from the description and drawings in which:

Fig. 1 is a front view in elevation of the improved necktie rack in the necktie engaging position.

Fig. 2 is a similar view in the released position.
Fig. 3 is a top view.

Fig. 4 is a cross-sectional view taken along the line 4—4 of Fig. 2.

Fig. 5 is a view similar to Fig. 4 with the hooks in engaging position.

Fig. 6 is a fragmentary view of the finger engaging end of the movable bar.

The necktie rack comprises a larger stationary bar 10 and smaller stationary bar 11 which may be made of wood, plastic or the like. Bar 10 is adapted to be connected to a suitable support by screws or the like passed through openings 12.

Movable bar 13 is connected to bar 10 through the hooked ends 14 of the outer hooks 15. Hooks 15 pass behind movable bar 10 and terminate in lateral extensions 16 which lock a tie by pressing against an adjacent hook as will be hereinafter described. Hooked ends 14 further serve as limits to the tie releasing position of the movable bar 13.

Between the outer securing members or hooks 15, the upper ends of a plurality of short hook members 17 are embedded in the material of the movable bar 13, are bent inwardly as at 18, passed

2

downwardly through the stationary bar 10 and then bent outwardly at an angle so as to form a hook or lateral extension 19 similar to the hook or extension 16.

5 The series of hook members 17 are maintained in lateral alignment along both elongated bars 10 and 13. Staggered in relation to each hook member 17 are each of a second series of hook members 20. Thus, between each hook 17 is embedded 10 in bar 13, a longer hook member 20, such hook member 20 extending through openings in both bar 10 and bar 11 and terminating in lower lateral extensions or hooks 21. Hook members 20 are considerably longer than hook members 17 so 15 that they may extend through bar 11. End, longer hook members 22 and 23 are further provided, the hook member 23 serving as an abutment for the adjacent hook 21 when the rack is in the necktie locking position, as illustrated in Fig. 1.

20 The necktie rack as described above doubles the capacity of the article without requiring any additional action in operating the device. Because of such increased capacity and the consequent weight of the neckties, it has been deemed 25 advisable to facilitate the operation by rendering the fingerhold form-fitting notwithstanding any particular grasp which a user may normally employ. It will be understood that the neckties are originally hung on the hooks when the rack is in 30 the open position illustrated in Fig. 2. Bar 13 is then shifted to the right as viewed in these figures so as to bring the respective series of hooks 19 and 21 into contacting and necktie locking relationship. This is normally accomplished by 35 pressing a finger against one end of bar 13, pressure on the left end serving to lock the neckties while pressure on the right end releases them. In the releasing action, the hooked ends 14 bear against the rear of movable bar 13 so as to limit 40 its movement.

In order to render the operation more convenient, a metal ferrule 25 is applied over each end of the movable bar. Ferrule 25 is concave on all of its five accessible sides. Thus, the 45 outer side 26 will normally be used by pressure of the operator's finger thereagainst. However, it may be desirable to pull the bar 13 with one hand while the finger of the opposite hand is pushing the opposite end of the bar. Accordingly, 50 the ferrule is formed with concave sides 27 so that it may be grasped by the thumb and forefinger of one hand. The top 28 and bottom 29 of the ferrule are further concave so as to provide another set of gripping surfaces. Concave surfaces 28 and 29 55 are preferably formed in situ so that the ferrule

may be simultaneously secured to the end of the movable bar. Thus, the ferrule will be forced on the bar with the top 28 and bottom 29 in flat condition and a suitable plier-like tool will press into the top 28 and bottom 29 so as to render them concave while causing them to bite into the wood of bar 13 and so as to simultaneously effect non-removable retention of the ferrule.

A necktie rack formed according to the above mentioned construction accommodates a large number of neckties and secures all of them against falling by locking them into position. Only a single, simplified movement such as described in the above mentioned patent is required to operate the rack notwithstanding its double capacity relative to the prior construction. The movable bar is formed as to facilitate finger actuation, this being of considerable advantage due to such increased capacity.

After the neckties are hung over both series of hooks, the movable bar 13 is actuated as aforesaid so as to rotate all of the hooks and lock the neckties against adjacent hooks. Inasmuch as the two series of hooks are disposed at different levels, all of the neckties are conveniently exposed so that a desired selection can be made with ease. This is particularly true in the locked position where the neckband portion of each necktie is clasped broadside and is thus presented or displayed in such a manner as to effectively isolate each one visually from the others by maintaining all of them side by side.

What is claimed is:

1. A necktie rack comprising an elongated stationary bar adapted to be secured to a support, an elongated movable bar parallel, juxtaposed, and spaced from said stationary bar, a pair of hook members connected to said movable bar and movably passed through the stationary bar for movably connecting said bars, a first series of hook members anchored in the movable bar in

lateral alignment with each other and passed through the stationary bar, a second series of hook members similarly anchored in the movable bar and in lateral alignment with each other and also passed through the stationary bar, each of said first series of hook members being shorter than the hook members of said second series whereby the respective series are aligned on different levels, both series of hook members being movable frontally for the suspension of neckties in display position upon the movement of said movable bar towards one side and for clamping the neckties between each two adjoining hook members of the same series upon the movement of said movable bar in the opposite direction, each hook member of said first series being arranged in staggered relationship with the hook members of said second series, and a second stationary bar below said first stationary bar and through which said second series of hook members is passed.

2. A necktie rack according to claim 1 and including a ferrule on at least one end of the movable bar so as to facilitate manual actuation thereof, said ferrule being five-sided and being concave at all of its sides.
